S. J. NIEMANN,

SWIMMING GLOVE,

APPLICATION FILED DEC. 11, 1920.

1,384,673.

Patented July 12, 1921.

UNITED STATES PATENT OFFICE.

SKJOLD J. NIEMANN, OF ST. PAUL, MINNESOTA.

SWIMMING-GLOVE.

1,384,673.

Specification of Letters Patent. Patented July 12, 1921.

Application filed December 11, 1920. Serial No. 429,971.

To all whom it may concern:

Be it known that I, SKJOLD J. NIEMANN, a citizen of the United States, residing at St. Paul, in the county of Ramsey and State 5 of Minnesota, have invented new and useful Improvements in Swimming-Gloves, of which the following is a specification.

This invention relates to swimming gloves and an object of the invention is to 10 provide gloves constructed of any suitable material which will provide a relatively great area for contact engagement with the water to assist a swimmer in propelling himself through the water and enabling him to 15 obtain more force in his swimming strokes.

Another object of the invention is to provide swimming gloves which lace upon the hands of the wearer and have a substantially crescent shaped pocket on the palm of the 20 glove which opens out and receives water therein on the propelling stroke of the swimmer and further increases the propelling power of the stroke.

Other objects of the invention will appear 25 in the following detailed description and accompanying drawings wherein:

Figure 1 is a plan view of the improved swimming glove.

Fig. 2 is a section on line 2—2 of Fig. 1.

Fig. 3 is a section through the palm of the glove taken on line 3—3 of Fig. 1.

Fig. 4 is a fragmentary section through the palm of the glove illustrating a modified form of the invention.

Referring more particularly to the drawing the improved swimming glove comprises a main body 1 split up the back, as shown at 2 and provided with eyelets 3 adapted to receive the lace 4 of ordinary construction 35 to firmly lace the glove on the wearer's hand so as to allow firm engagement of the glove with the wearer's hand without unnecessary and irritating binding action of the glove.

The body 1 is provided with the usual 45 finger sockets 5, and has webs 6 extending between the finger sockets forming a webbed glove, as shown in Fig. 2 of the drawings, the finger sockets 5 are preferably formed of one piece of material bent 50 about to provide the necessary finger receiving shaft and having its overlapping edges 7 stitched or otherwise suitably connected and as also shown in Fig. 2 of the

drawings the edges of the webs 6 are positioned between the overlapping edges 7 of 55 the finger sockets 5 stitched thereto by the stitching which connects these overlapping edges providing secure interlocking connection between the finger sockets and webs 6. If the glove is made of rubber or analogous 60 material it is to be understood that the overlapping edges 7 of the webs 6 may be vulcanized for securely connecting them and it is to be further understood that any approved means of connecting these edges in 65 the manner specified may be employed without departing from the spirit of this invention, and depending upon the kind of material from which the glove is made.

Attached to the palm of the glove is a substantially crescent shaped pocket 8 and the convex edge 9 of which is rigidly and securely attached to the palm of the glove while the concave edge 10 is free from engagement with the glove and preferably has 75 its edge portion flattened back upon itself, as shown at 11 to reinforce the edge portion to facilitate the holding open of the lower concave edge of the pocket to permit the pocket receiving water upon a propelling 80 stroke of the swimmer where the glove forms an abutment of water against which the power of the swimmer's stroke impinges and consequently increases the propelling 85 power of the stroke. The pocket 8 is constructed so that it will close when the hand is lying flat and the fingers separate but will open when the fingers are slightly bent as in making a propelling stroke. However, if it is desired, means may be employed for 90 maintaining the pocket open so as to insure receiving of a body of water therein and in Fig. 4 of the drawings such means is illustrated which comprises V shaped springs 20, two of which springs are indicated by dotted lines in Fig. 1 of the drawings so as to show their relative positions in the pocket. These springs 20 are of sufficient tension to maintain the pocket open to receive water but are weak enough to allow the pocket to 100 close when a receding movement of the glove is made after a power or propelling stroke of the swimmer.

It is, of course, to be understood that the invention may be constructed in various 105 other manners and the parts associated in

different relations and therefore, I do not desire to be limited in any manner except as set forth in the claims hereunto appended.

Having thus described my invention what 5 I claim is:

1. In a swimming glove, a body having a wrist portion, finger stalls thereon, webs between the finger stalls, said finger stalls having overlapping edges, the edges of said 10 webs being inserted between and attached to the overlapping edges of the finger stalls, and a substantially crescent shaped pocket forming member attached to the palm of said glove with its concave portion opened 15 out toward the wrist portion of the glove.

2. In a swimming glove, a split body, a lace for lacing the body upon the wearer's

hand, and a substantially crescent shaped pocket forming member attached to the palm of the glove and opening out toward 20 the lacing of the glove.

3. In a swimming glove a body comprising a palm and a wrist portion, and a pocket forming member on the palm of the glove opening out toward the wrist portion. 25

4. In a swimming glove a body comprising a palm and a wrist portion, and a pocket forming member on the palm of the glove opening out toward the wrist portion, and yieldable means for maintaining said pocket 30 open in the movement of the glove in a predetermined direction.

In testimony whereof I affix my signature.
SKJOLD J. NIEMANN.
